UNITED STATES PATENT OFFICE.

JOHN POND, OF SUMMERSIDE, PRINCE EDWARD ISLAND, CANADA.

TIME-INDICATING DEVICE.

Application filed December 3, 1924. Serial No. 753,693.

This invention relates to time determining devices and has particular reference to a device by means of the relative position of which with respect to the sun, time may be readily and accurately determined.

The invention comprehends a device including the usual clock dial or face with which the ordinary hour and minute hands are associated and cooperate to indicate time, in conjunction with actuating means connected therewith and manually operable in accordance with the position of the sun with respect to said device whereby to move the hands to a position for determining the correct time.

It is therefore an object of the present invention to provide a device or instrument for determining time by the usual clock face or dial and hands by means of an actuating device operable in accordance with the position of the sun.

The invention furthermore contemplates a portable device of the character described in which means is provided for properly positioning the same prior to the setting of the actuating means in accordance with the position of the sun.

The invention furthermore comprehends a device of the character set forth which is comparatively simple in its construction, inexpensive to manufacture and produce and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 illustrates a plan view of a portable device constructed in accordance with the invention.

Fig. 2 is a longitudinal sectional view therethrough taken approximately on the line indicated at 2—2 in Fig. 1.

Fig. 3 is a modified form of the pointer.

Fig. 4 is a plan view illustrating a stationary device or instrument.

Referring to the drawings by characters of reference 10 designates a casing which is provided with a closed lower end 11, a horizontal partition 12 and a crystal or transparent upper wall 13. The upper face of the horizontal partition wall 12 is provided with an annular series of characters 14 defining an ordinary clock dial. The partition is provided with a bearing opening 15 concentric to the annular series of characters 14 through which a tubular arbor or shaft 16 extends and with which the usual hour hand 17 is connected, the said arbor or shaft 16 being connected at its lower end beneath the partition 12 with a pinion or gear 18. Extending through the tubular arbor or shaft 16 concentrically is a second shaft 19 or arbor 19 which protrudes upwardly beyond the shaft or arbor 16 and has connected therewith the usual minute hand 20. The lower end of the shaft or arbor 19 is mounted in a step bearing 21 in the upper face of the bottom wall 11 of the casing. The shaft or arbor 19 has secured thereto immediately below the gear or pinion 18 a pinion or gear 22. A counter-shaft 23 is mounted vertically in bearings 24 in the bottom wall 11 and partition 12 alongside of and parallel to the shaft or arbor 19 and said counter-shaft 23 has secured thereon super-imposed gears or pinions 25 and 26 the former meshing with the gear or pinion 18 and the latter with the gear or pinion 22 whereby the shaft or arbor 19 is driven from the shaft or arbor 16 so that the former together with the minute hand 20 makes twelve complete rotations for every rotation of the arbor 16 and hour hand 17. At one side of the dial face, the partition 12 is provided with a vertical bearing opening 27 through which a shaft 28 extends having its lower end mounted in a step bearing 29 in the upper face of the bottom wall 11 of the casing. On the said shaft immediately below the partition 12 a gear or pinion 30 is secured disposed in the same plane with the gear or pinion 18 and meshing therewith, the said gear 30 being geared with respect to the pinion 18 so

that one complete rotation of the gear 30 rotates the pinion 18 two complete revolutions. Immediately below the gear or pinion 30 a bevel gear 31 is keyed to the shaft 28 and the same meshes with a bevel pinion 32 which is mounted on a horizontal shaft 33 extending through a bearing opening 34 in the side wall of the casing and through a bearing bracket 35 projecting upwardly 10 from the bottom wall 11. The outer end of the shaft 33 has secured thereto a knurled manipulating nut 36 whereby an operator may manually rotate the shafts 33 and 28 and the arbor 16, counter-shaft 23 and 15 arbor 19. The upper end of the shaft 33 which projects above the partition 12 has mounted thereon a pointer element 37 which is preferably in the nature of an extremely thin sheet of material disposed vertically 20 with its lower edge in a plane above the plane of the minute hand 20. The pointer element 37 is preferably provided with an upstanding bearing pintle 38 which is disposed concentric to the axis of the shaft 28 25 and is designed to constitute a bearing for a magnetic compass needle 39. The upper face of the partition 12 is provided with an indicating character 40 disposed in a line in direct prolongation from the character 12 30 of the clock dial for the purpose of co-operating with the compass needle 39 to properly orientate the device. It is of course understood that the compass element is only employed where the device is a portable one.

35 In use and operation of the device heretofore described, after the same is orientated, that is after the compass is employed to position the device so that the clock dial character 12 is due north, the manipulating nut 40 or handle 36 is rotated to position the pointer element or blade 37 with respect to the position of the sun so that no shadow is cast on either side of said blade or pointer 37. It will be found that due to the gearing of the 45 gears 30, 18, 25 and 26 upon the adjustment of the blade or pointer element 37, the hands will properly coact with the clock dial characters to correctly indicate the time. This is indicated in Fig. 1 in which the position 50 of the sun S is due east and as shown the blade or pointer element 37 having been correctly manipulated with the instrument or device properly orientated the minute and hour hands 20 and 17 indicate the time as 55 six o'clock a. m. From this it will follow that when the sun is due west the position of the blade or pointer element 37 will be the same as indicated denoting by the hands and dial that the time is six o'clock p. m. It thus 60 follows that by means of the instrument or device heretofore described accurate determination of the time may be obtained with ordinary clock dial readings.

65 In the modified form of the invention illustrated in Fig. 3 the pointer or blade ele-

ment 37^a is provided at one end with an up-standing sight lug 37^b which may be employed in connection with the pintle element 38^a as a sighting means in lieu of depending upon setting the device by eliminating the casting of the shadow on the sides of the blade or pointer element. The sighting of the pointer 37^a may be accomplished if desired by a means of telescopic sights, reflecting surfaces, lenses or other defining devices 70 may be attached thereto to aid in correctly aiming at the center of the sun or at an imaginary vertical line drawn therefrom to the horizon.

75 In the form of the device illustrated in Fig. 4 the instrument 41 is of a stationary type provided with a clock face or dial 42, the minute and hour hands 43 and 44 and a finder blade or pointer element 45. In this form of device it is of course appreciated 80 that the necessity of using the compass for orientation is obviated. In this form the device works in exactly the same manner as that heretofore set forth, namely the blade or pointer element 45 is sighted with respect to the position of the sun S and is operatively connected with the hour and minute hands to indicate the time by reading of the hands in connection with the dial face.

85 I claim:

90 1. A time determining device including a clock dial, clock hands associated and adapted to cooperate therewith to denote time 100 readings, manipulating means connected with said hands for actuating the same and finder means connected with the actuating means adapted to be positioned in a predetermined manner relative to the sun whereby to dispose the clock hands relative to the dial to indicate the time.

105 2. A time determining device comprising a combination with a clock dial and minute and hour hands associated with said dial for denoting the usual time readings, of means connected with said hands and operable to 110 be positioned in a predetermined manner relative to the sun, to simultaneously move the hands over the dial to relative positions for indicating the time of day in accordance with the position of the sun.

115 3. A time determining device comprising a clock dial, hands movable over said dial for denoting the usual time readings, a rotary pointer blade adapted to be positioned in a predetermined manner with respect to the sun and a connection between said pointer blade and the clock hands for simultaneously moving the same with the pointer to denote the time in accordance with the position of the sun with respect to said device.

120 4. A time determining device comprising a clock dial, hour and minute hands movable over said dial for denoting the usual time 125 readings, a rotary pointer blade adapted to be positioned in a predetermined manner

with respect to the sun and a connection between said pointer blade and the clock hands for simultaneously moving the same with the pointer to denote the time in accordance with the position of the sun with respect to said device, said connection comprising a train of gears by means of which the hour hand is rotated two revolutions for every single revolution of the pointer and by means of which the minute hand is rotated twelve revolutions for every single revolution of the hour hand.
